UNITED STATES PATENT OFFICE.

ISRAEL B. LEIBSON, OF NEW YORK, N. Y.

ACTUATING DEVICE.

1,037,271.

Specification of Letters Patent. Patented Sept. 3, 1912.

Application filed January 31, 1911. Serial No. 605,765.

To all whom it may concern:

Be it known that I, ISRAEL B. LEIBSON, a citizen of the United States, residing in the city of New York, county and State of New York, have invented a new and useful Actuating Device, of which the following is a specification.

My invention relates to means of transmitting motion from moving railway vehicles to mechanism on or along the track for throwing switches, setting signals or operating any other apparatus along the permanent way of a railroad; but my invention does not extend to any part of the apparatus to which motion is to be transmitted beyond the connection of my device to such apparatus.

The objects of my invention are: To provide a device of the nature mentioned that will operate effectively at all varying speeds of the locomotive or car. To provide a device that will overcome or avoid the momentum of the moving car or train when the motion is transmitted, so that even when operated from the fastest moving express there will be no danger of injury to any of the mechanism from the necessary impact. To provide a device that will automatically control the motion transmitted at all varying speeds of the moving vehicle, and temporarily lock the apparatus at the instant the required motion to operate the mechanism is completed. To provide a device to transmit motion, as above set forth, in which, even under the most unfavorable conditions of swaying and lurching of the moving car, the contact surfaces of the part of the device attached to the car and the part attached to the track will not fail to come in contact to their full extent, when contact is required. To provide a device to transmit motion, as above set forth, in which the exposed portion on the track will be free from danger of clogging or injury under such conditions as would not be sufficiently unfavorable to make the road itself impracticable.

Further objects and advantages of my invention appear in the detailed description hereafter.

The invention may be summarized as consisting of a rail on the track, connected with the mechanism to which motion is to be transmitted, which rail is located parallel to the track rails and capable of sliding or moving freely (as on rollers or ball bearings) back and forth in the direction of the

track, and a wheel connected with the locomotive or car, revolving in the direction of the moving car and at a peripheral velocity greater than that of the car wheels, which wheel may be lowered at the will of the engineer or motorman to come in contact with said movable rail with sufficient pressure to cause the friction between it and the movable rail to exceed and overcome the resistance of the rail and the mechanism with which it is connected to the motion of the said additional wheel, as hereinafter more fully described.

In the accompanying drawings forming part of this specification, Figure I is a plan of the device; Fig. II is a side elevation; Fig. III is a sectional view of the movable rail on an enlarged scale; Fig. IV is a longitudinal section of one end of the movable rail on the enlarged scale; Fig. V is a perspective view of one end of the lower member of the movable rail, and Fig. VI is a plan, on a reduced scale, of a track and switch, showing two movable rails in position and their direct connection with the switch.

Similar letters and figures refer to similar parts throughout the several views.

A A represent two car wheels, B their axle revolving with the wheels, and C C gear wheels the diameters of their pitch circles being half that of the car wheels A A, and keyed or fastened to the axle B so that they will revolve with it but prevented from moving laterally; two frames D D are mounted on the axle which passes through the bearings E E, E E on each side of the gear wheels C C so that the frame may swing vertically but cannot move laterally; the bearings are provided with oil cups e e, e e. In each frame is journaled an idler F whose pitch circle diameter equals that of C, and a pinion G of half the diameter of F or C, which pinion has keyed to its axle the wheel H of about the same diameter as that of the car wheels A A to whose axle it is geared; so that it revolves in the direction of the car wheels, and having double the angular velocity of the wheels A A and about the same diameter, has about double the peripheral velocity of the car wheels. I do not, however, claim that the peripheral velocity of the wheel H must double that of the car wheels; for obvious reasons that will appear during the complete description of the device a peripheral velocity of from one tenth to one fifth in excess of that of the car

wheels may, under most conditions, be more economical, and the double velocity given in the illustration is only for the purpose of presenting a more vivid mental picture of the operation of the device while the car is in motion, for the relative motion of the wheel H will then be due only to the excess peripheral velocity.

The gear wheel C and the frame D are located on the axle so that the wheel H will pass through the vertical plane of the movable rail hereinafter described in detail; and, to allow for the deviation of the car wheels on the track rails, the wheel H is to be about one inch wider than the movable rail.

At one end of the frame D, and rigid, with it, is the rod I, which is connected with the piston rod J of the air cylinder K, the air cylinder K is rigidly attached to the cross-bar L which is rigidly attached to a bar M in the truck frame which bar M is rigidly attached to the axle-boxes. In order to allow for as much as one inch side thrust due to possible wearing of brasses in axle-boxes, the end of piston-rod J is bifurcated, and the space between the prongs *j* is two inches wider than the rod I; and to allow for the slightly circular motion of the end of the rod I, the bore *i* for the pin *a* is elongated. The air cylinder K is supplied through the pipe and flexible hose *k* through the four-way cock N within reach of the motorman or engineer, by which he may allow compressed air to enter or escape from either cylinder, the flexible hose permitting variation in motion of car frame and car truck. The pipe *n* from the four-way cock leads to the air reservoir.

The air cylinder K is attached to the rigid bar L so that when compressed air is admitted, and the piston rod has forced down the wheel H to its full extent, the lowest point in the periphery of the wheel will be one-half inch above the surface of the track rails. The spring O, inside the air cylinder K, will draw the piston-rod and wheel H back into position, when the compressed air is allowed to escape from the cylinder.

Between the track rails P P' are located the movable rails R R', each consisting of a lower member *s* rigidly fastened to the track, ball bearings *q* *q* *q* and an upper member *r* rolling freely on the ball bearings. The movable rails are one inch higher than the track rails. The lower member *s* has a base, web and head in its central portion, but only a base and part of the web at its ends, as shown in Figs. IV and V, so as to permit the upper member *r* to be completely closed at its ends, and to protect the inner surfaces of the two members. The head of the lower member *s* has a very slight concave 1 at its top, but no more than is sufficient for a groove for the ball bearings, then

slopes downward along the side 2, so that foreign matter cannot lodge on its surface, and then turns up obliquely forming the side 3 and unites with the web of the rail in an acute angle, the corners being somewhat rounded so as not to retain foreign substance.

On the head of the lower member are lugs 4, 4, 4, to keep the ball bearings from contact with each other, and the lugs are a little farther apart than the distance 70 the upper member *r* is to travel. The upper member at its ends slopes one inch in about two feet, and is then closed at its extreme ends as shown in Fig. IV at 2. Its bearing surface 5 is the same as that of an ordinary 80

T rail. From its bearing surface it slopes downward forming the side 6, and then down and under the head of the lower member, forming the side 7; its inner surface also slopes down along the side 8, and then 85 again down and under the head of the lower member, forming the side 9, but does not come in contact with the lower member. A trap is thus formed protecting the inner surfaces from any foreign solid substances; 90 for, if even a cinder were blown against the web of the lower member, and would rise to enter between the surfaces, it would be stopped in the angle formed by the side 3 with the web, and then be carried down by 95 the web or the sloping side 8 of the lower member, to the sloping side 9 of the upper member, and then down, perhaps again striking the side of the web on its way down and out. Water, and consequently mud, 100 cannot accumulate between the sloping surfaces of the upper and lower members; a complete flood, though adding somewhat to the resistance of the rails, cannot choke ball bearings, and the water would drain off of 105 itself. The lower member is longer than the upper member by a little more than the distance that the upper member will have to travel to operate the mechanism on the track, and at each end sufficient of the head 110 and part of the web of the lower member is removed to permit the closed portion of the upper member to pass over. And the entire sliding rail is made longer than necessary 115 to operate the mechanism, so as to automatically lock the same, as hereinafter shown in the mode of operation. To the upper members are suitably attached arms *t* *t*, or *t'* *t'*, which are connected with the levers U, U, 120 pivoted at V, which levers are connected by 120 means of the cross-bar W to the mechanism to be operated, as the switch rails X X'.

In order to operate the device as, for instance, to throw the switch in Fig. VI from the position shown in the dotted line, the engineer on a high speed locomotive, seeing at a distance, by the signal, that the switch is open to the branch line, and that he will have to close same in order to proceed on the main line, without reducing speed, turns 130

the cock N to admit compressed air through the flexible hose and pipe *k* to the air cylinder K on the right. The compressed air immediately forces the piston down to its lower end, and the piston-rod forces down the frame D so that the wheel H is forced down as far as it can go, that is, to one-half inch above the track rails. The wheel H is in the same vertical plane as the movable rail on the right, and is prevented from lateral movement, as heretofore set forth. The movable rail reaches to one inch above the track rails, so that the wheel H reaches one half inch below the bearing surface of the movable rail, and when the locomotive reaches the movable rail the wheel H must come in contact with it; for the wheel cannot pass out of the vertical plane of the movable rail, because it is connected with the axle and is prevented from lateral movement, and the only possible deviation of the axle, due to the deviation of the car wheels on the track rails, is made up by the wheel H being one inch wider than the movable rail; neither can said wheel be thrown above the movable rail by any vertical motion of the car frame over the trucks, for the reason that the wheel is held in position at one end by the car axle, which maintains a uniform distance above the rails, and at the other end by the air cylinder that has rigid connections with the axle box, which also maintains a uniform distance above the rails. The half inch that the wheel H extends below the bearing surface of the movable rail will allow for any difference in the relative surfaces of the movable and track rails when the track sinks from the trackman's surface to the bearing surface when a hundred-ton locomotive passes over it, also for any vertical vibration of the rigid bars mentioned, in the truck frame, and any slight bending of the movable rail itself. The wheel H and the movable rail cannot, therefore, fail to come in contact to their full extent when air is admitted into the cylinder. Now, if the wheel H had the same peripheral velocity as the car wheels, it would, on coming in contact with the inclined surface (of one inch in about twenty-four) at the end of the movable rail, mount and roll over same with the car; but, as its peripheral velocity is greater than that of the car wheels, it would tend to draw the car over the movable rail faster than its motion on the track rails; but the weight or resistance of the car holds it back and prevents the wheel H from rolling over the movable rail, and would cause it to slip thereon, if it were not that the upper member of the movable rail is loose, and the pressure from the air cylinder is great enough to overcome the resistance of the rail (and the mechanism to which it is attached) to the motion of the wheel H, so that it draws the movable rail under it toward the rear of the car. The movable rail in turn moves the levers V from *v* to *v'* which in turn shift the cross-bar that moves the switch until the switch-point X' is stopped by the track rail P', and the main line is opened and the branch line closed. After passing the switch-point, the engineer allows the compressed air to escape from the cylinder, and the spring O raises the wheel H to its normal position. Should the engineer not have had time to allow the compressed air to escape from the cylinder before passing over the rails at the crossing, the wheel H, being one-half inch above the surface of the track rails will easily clear them. To have thrown the switch to open the branch line, the engineer would have had to admit air into the cylinder K on the left to operate the sliding rail R on the left. Further, the instant the switch point X' is fully thrown, and is stopped by the track rail P' from moving farther, it also stops the movable rail R', so that the resistance of the movable rail (wherever this expression is used its upper member *r* is meant) becomes too great and overcomes the friction between it and the wheel H, so that the wheel then slips over it partially (to the extent of the excess peripheral velocity only), for the rest of its length; but always with the same pressure, so that the switch-point X' is kept automatically pressed against the track rail P'; and, by extending the movable rail beyond the switch point, the switch can be automatically locked until the last wheel of the car has passed the switch point.

The mechanical construction of the movable rail as already pointed out, and its shape and form as shown in the drawings, is such as to prevent clogging under any ordinary conditions; and any great wash-out carrying sand or gravel that could work its way in between the surfaces of the two members of the rail to impair their operation, would in less time choke the switch and make the road itself impracticable.

Assuming that the resistance of the rail and the attached mechanism is one hundred pounds (though by a system of levers it may be made much less), and that oil has not only been dropped on the movable rail but maliciously or accidentally spread over its entire bearing surface, then taking the coefficient of friction between metallic surfaces that have been oiled as about eight per cent., a pressure or static wheel weight by the wheel H on the movable rail of but fifteen hundred pounds will be more than sufficient to operate the mechanism with the absolute certainty of a physical law.

Considering the rotary motion of the wheel H, the angle of motion of its center of inertia to the normal at point of contact on the inclined end of the rail, and its rela-

tively small weight, whatever the speed of the car, the impact of the wheel H on the movable rail will be but a small fraction of that of the drivers of a locomotive on the 5 ends of rails at their joints.

In the foregoing description and drawings but one embodiment of my invention has been presented, sometimes showing enlarged measurements and speeds, as already 10 set forth, and sometimes conditions unfavorable to the application of the invention, but for the purpose of showing its effective operation under any conditions that might arise, and to better explain the application 15 of principles the use of which is entirely new for the purpose of transmitting motion from a moving railway car or locomotive to mechanism on or along the track. But different mechanisms may be employed to carry 20 out the main features of my invention. Thus, the speed of the additional wheel H does not affect the friction required to draw the movable rail, but, after a certain limit a higher speed increases the resistance of the 25 movable rail, and a lower speed requires a lengthening of the rail, whose weight will then add to the resistance; the excess peripheral velocity to be given to the wheel H will depend on the different mechanisms on 30 the road to be operated, that is, a velocity that will be most economical for all the mechanisms in the aggregate. Also, where the device is attached to a spring switch which will draw the movable rail back into 35 position, but one movable rail is required instead of two. Or, a lever may be used for giving pressure instead of an air cylinder and its appurtenances; or, where the mechanism to be operated is very light, the wheel 40 itself may be weighted; or the necessary power for revolving the wheel instead of being received from the axle of car wheels of sufficient weight, may be obtained from a dynamo; and many other mechanical equivalents that would be too numerous to mention in this specification may be adopted, 45 without changing the main features of my invention.

I claim:

50 1. A device for transmitting motion from a moving railway car or locomotive to mechanism on or along the track, consisting of a rail connected with said mechanism on the track and capable of sliding or moving 55 freely back and forth in the direction of the track, and a wheel attached to the car or locomotive, revolving in the same direction as and at a peripheral velocity greater than that of the car wheels, and capable of being 60 brought in contact with the sliding rail at the will of the engineer or motorman with sufficient weight or pressure for the friction between it and the sliding rail to overcome

the resistance of the sliding rail and the attached mechanism to the motion of the said 65 wheel, substantially as set forth.

2. A device for transmitting motion from a moving railway car or locomotive to mechanism on or along the track, consisting of a rail connected with said mechanism on 70 the track and capable of sliding or moving freely back and forth in the direction of the track, a wheel attached to the car or locomotive, and means for revolving said wheel with sufficient power, and in the same direction as and at a peripheral velocity greater 75 than that of the car wheels, so that when brought in contact with the sliding rail with sufficient weight or pressure, the relative motion of the said wheel will be transmitted 80 to the said rail, substantially as set forth.

3. A device for transmitting motion from a moving railway car or locomotive to mechanism on or along the track, consisting of a rail connected with said mechanism on 85 the track and capable of sliding or moving freely back and forth in the direction of the track, a wheel attached to the car or locomotive, revolving in the same direction as and at a peripheral velocity greater than 90 that of the car wheels, and a means for bringing said wheel in contact with said movable rail with sufficient pressure or weight to cause the friction between them to overcome the resistance of the sliding rail 95 and attached mechanism to the motion of the said wheel, substantially as set forth.

4. In a device of the nature described, a movable rail consisting of a lower member rigidly attached to the track, ball bearings, 100 and an upper member; said lower member having a base, web and head in its central portion, and a base and part of the web at its ends, the upper side of the head being convex, with a slight concave at the top, and the under side of the head turning up obliquely to meet the web, and spaced apart lugs on said head; the upper member sloping at its ends, and having an outer surface flat at the top, then extending out and under the 110 head of the lower member, and an inner surface curving out and under the head of the lower member, for the purposes set forth.

5. In a device of the nature described, a car axle, a frame mounted on said axle and capable of swinging vertically, a wheel set in said frame, and a system of gears connecting said wheel to said axle, so that it will revolve with said axle with a peripheral velocity greater than that of the car wheels, 115 120 for the purposes specified.
